CLAIM

The ornamental design for an egg table, as substantially shown and described.

DESCRIPTION

FIG. 1 is a perspective view of an egg table of the present invention.

FIG. 2 is a top view of the egg table of the present invention.

FIG. 3 is a bottom view of the egg table of the present invention.

FIG. 4 is a rear elevation view of the egg table of the present invention.

FIG. 5 is a front elevation view of the egg table of the present invention.

FIG. 6 is a side elevation view of the egg table of the present invention; and,

FIG. 7 is an opposite side elevation view of the egg table of the present invention.

The above drawings are illustrative of the invention, and define the spirit and scope of the invention.
